UNITED STATES PATENT OFFICE.

CARL HAUGK, OF WURZEN, SAXONY, GERMANY.

CIGAR-MACHINE.

SPECIFICATION forming part of Letters Patent No. 289,412, dated December 4, 1883.

Application filed February 20, 1883. (No model.) Patented in Germany March 29, 1882, No. 20,189.

To all whom it may concern:

Be it known that I, CARL HAUGK, a citizen of Germany, residing at Wurzen, in Saxony, in the Empire of Germany, have invented a new and useful Improvement in Cigar-Machines, of which the following is a specification.

My invention relates to cigar hand-rolling machines; and it consists in the combination of a vibrating shaft carrying rods having springs and supporting a pressure-roller which carries a bight in an apron with the frame of the machine, whereby the desired pressure or friction in the rolling of the cigar is produced.

In the accompanying drawings, Figure I is aside elevation of my improved cigar-machine. Fig. II is a top view of the same. Fig. III is a vertical section at line A A, Fig. II, and Fig. IV is a vertical section at B B, Fig. II, with the pressure-roller at the extreme end of its section.

Similar letters represent similar parts in all the figures.

In a suitable frame, F, a shaft, a, is arranged, supported in bearings b b, capable of being raised or lowered by means of suitable set-screws, e e. Upon this shaft a drum or pulley, m, is attached, around which a band, g, is wound, the lower end of which is attached to a suitable treadle (not shown in the drawings) for the purpose of turning this shaft the required distance around whenever the treadle is acted upon. A spring, h, wound around a shaft, h', and connected through a flexible rod, h'', with the drum m, causes the drum m and shaft a to turn back again in the position shown in Fig. IV as soon as the pressure or action upon the treadle is removed.

To the ends of the shaft a rods c c are attached, provided with spring-cases f f, the upper ends of said rods c c carrying the pressure-roller d. The spring-cases f f contain spiral springs 2 2, acted upon by the case-caps 3 3, whereby the action of said springs 2 2 may be increased or diminished, and thereby increasing or diminishing the pressure of the roller d during its action with the rolling-band i.

The upper surface of the frame F is made partly concentric with the shaft a at F', and with a recess, F'', near the after end, and with a suitable opening, F''', near the back for the

rolling-band i to pass to the interior of the frame F. At the point p of the frame F the rolling-band i is attached, passing over the top surface of said frame and over a guiding-roller, r, placed in the opening F''', then into the interior of the frame F, the end of said band i being attached to a roller, o. This rolling-band i passes likewise around a bar or strap, k', attached to suitable springs, k, wound around a shaft, n, to keep said rolling-band i always tight and properly stretched. The rollers or shafts o and n are provided with suitable ratchet-wheels, q q', in connection with pawls, whereby the position of said shafts may be changed and regulated, and by which means the working part of the rolling-band i may be lengthened or shortened, as may be required.

The tobacco, with the end of the wrapper or binder for the cigar, is placed upon the band i and pressed into the recess F'', forward of the roller d, (when in a position as shown in Fig. IV,) when motion being given to the treadle and band g, said roller d will move first into the position shown in Fig. I, where the rolling-band i surrounds the tobacco t, forming a bight, and a further motion of the roller d over the concentric surface F' will roll or wind the wrapper or binder around the tobacco until the roller d arrives at the end of this concentric surface F', as shown in dotted lines in Fig. I, when the finished cigar will be delivered in the receptacle l, attached to the end of the frame.

By the above described arrangement for lengthening or shortening the rolling-band i, the bite to receive the tobacco, as shown in Fig. I, can easily be regulated according as a large or small, or, more properly, a thick or thin cigar is to be manufactured or operated upon, and by the arrangement of the spring-cases f f in the rods c c and movable bearings of the shaft a, the pressure of the roller d can easily be increased or diminished, as may be desired.

What I claim as my invention, and desire to secure by Letters Patent, is—

1. In a cigar-machine, the movable shaft a, with rods or levers c, provided with spring-cases f, and the pressure-roller d, in combination with the rolling-band i and frame F, arranged

to operate in the manner and for the purpose substantially as set forth.

2. A cigar-machine consisting of the frame F, the upper surface of which is arranged as described, the rolling-band *i*, one end of which is fastened to the front of the frame and the other end, after passing around a spring-bar or strap, *k'*, to a shaft, *o*, and the pressure-roller *d*, attached to vibrating rods *c c'*, having

springs, the whole being combined and arranged to operate substantially in the manner and for the purpose herein described and set forth.

CARL HAUGK.
